UNITED STATES PATENT OFFICE.

ANDERSON BOOZE, OF BUCHANAN, VIRGINIA.

IMPROVEMENT IN STILLS FOR SPIRITS.

Specification forming part of Letters Patent No. 120,701, dated November 7, 1871.

To all whom it may concern:

Be it known that I, ANDERSON BOOZE, of Buchanan, in the county of Botetourt and State of Virginia, have invented a new and Improved Alcohol-Still; and I do hereby declare the following to be a full, clear, and exact description of the same, reference being had to the accompanying drawing making a part of this specification, in which—

Figure 1 is a transverse sectional elevation, and Fig. 2 is a horizontal section.

This invention relates to a cap for a still, said cap receiving the vapor from the steamed mash in the still and conducting such vapor through a coil of pipe, wherein it is condensed, and from which it flows in the condition of singlings to the low-wine room, said cap also receiving, through a pump, singlings from the low-wine room, and vaporizing them by means of the heat of the aforesaid coil, which vapor is discharged through a separate pipe in the form of alcohol, the residuum or feints from the heated singlings being drawn off from the cap through a tube at its lower end.

Referring to the drawing, *a* is the cap, the same having a top and bottom each with a central opening. The opening in the bottom of the cap forms the lower mouth of a hollow cone, *b*, placed within the cap, and extending nearly to its top, from the upper end of which cone passes a pipe, *c*, which descends in a coil around the cone and within the cap, and passes through the side of the latter near its bottom, said coil being connected with the low-wine room, and consequently discharging into the latter the singlings condensed within the coil from the vapor that enters the latter from the steamed mash in the still below. A pipe, *d*, connecting with the low-

wine room, pours the singlings pumped from the latter into the top of the cap, wherein the singlings, being subjected to heat from the coil *c*, give off alcohol in vapor, which passes through the orifice at the top of the cap, and thence, by a pipe, *e*, to the alcohol-worm. A pipe, *f*, opening out of the bottom of the cap, gives exit to the feints or residuum from the heating of the singlings.

If it is thought better to return the feints to the still for redistillation this may be done by means of the pipe *g*, opening out of the cap *a* at the opposite side from the pipe *f*.

This process I maintain to be superior to that in which the vapor from the still comes directly in contact with the singlings, because in the latter case vaporization takes place too fast, and in consequence the vapor becomes charged with impurities from the singlings and an inferior quality of alcohol is the result.

Having thus described my invention, what I claim as new, and desire to secure by Letters Patent, is—

1. The process of evaporating singlings by means of the vapor arising from steamed mash, when the singlings are received in a cap above the still and the vapor passes through a coil of pipe placed within said cap, as described.

2. The combination of the cap *a*, cone *b*, and coil *c*, constructed and operating as specified.

To the above specification of my invention I have signed my hand this 13th day of May, 1871.

ANDERSON BOOZE.
